FIRE ALARM THERMOSTATIC CONTACT

Herbert G. Hunt, New York, N. Y.

Application March 26, 1937, Serial No. 133,197

7 Claims. (Cl. 200—142)

This invention relates generally to automatic fire alarm systems and more particularly to thermally controlled electrical circuit closing devices especially suited for use in connection therewith.

5 Among the objects of this invention is the provision of an improved heat controlled electrical circuit closing device which is solely affected by heat and possesses the quality of being able to remain comparatively unaffected by the passage 10 of time.

Another object herein is the provision of an alarm controlling unit which may be quickly and easily replaced after the unit has been acted upon by heat.

15 Still another object of the present invention is the provision of structure which is constant and uniform in sensitivity and action, and which when actuated by the requisite amount of heat closes an electrical circuit of very low resistance 20 and said circuit is closed in a positive manner.

Among the features of the invention is the inclusion of the present device in the ordinary household or office annunciator systems so that the same electric bell, power source, and portions 25 of the wiring may be used with a consequent reduction in installation and maintenance cost.

The present circuit closing unit permits of simple manufacture with corresponding economies in production so that with low initial cost sufficient units may be used at various points to give 30 adequate protection.

These objects and further features and advantages will more fully appear in the progress of this disclosure and as pointed out in the appended claims.

In the drawing:

Figure 1 is a front elevational view of a preferred embodiment of the invention with the cover removed.

40 Figure 2 is a plan view of Figure 1 with the cover shown in central horizontal section.

Figure 3 is a view similar to Figure 1 with the cover in place.

45 Figure 4 is an enlarged fragmentary view of Figure 1 showing the fusible material and adjacent parts.

Figure 5 is a vertical sectional view of Figure 3 as seen from the plane 5—5 thereon.

50 Figure 6 is a developed view, reduced in size, of the cover.

Figure 7 is a schematic diagram of an electrical circuit in which the present invention may be utilized.

The automatic circuit closing device generally 55 represented by numeral 10 is adapted to be

quickly and conveniently placed upon or removed from a mounting plate therefor generally indicated by numeral 11. Mounting plate 11 is preferably substantially oblong in shape and is composed of any suitable insulating material such as fibre, Bakelite, molded plastic, wax treated wood or ceramic. Mounting plate 11 may be readily affixed to any vertically disposed surface by means of flat head screws (not shown) which penetrate the countersunk orifices 12. While 10 some deviation from the vertical may be permitted in the surface to which the plate 11 is affixed, best operation of the device will be obtained when said surface is vertical as will be more fully understood below. The mounting 15 plate 11 is provided with two electrical terminal screws 13 and 14 and two circuit closing device mounting screws 15 and 16. The screws 13 to 16 inclusive are threadedly mounted in the front surface of the plate 11 in orifices 17. Screws 13 20 and 15 and 16 and 14 respectively are electrically connected by short contact strips 18 and 19. The strips 18 and 19 are preferably not thick and serve to conduct electricity from the electrical terminal screws to the mounting screws. 25

The device 10 is built upon a base plate 20 which may be composed of any suitable insulating material and preferably of a vulcanized sheet fibre which permits of some compressibility rather than electrical insulating materials which 30 are brittle. Mounted upon plate 20 is an irregularly shaped open circuit contact plate 21, the configuration of which may best be seen in Figures 1 and 2 of the accompanying drawing. Plate 21 is maintained in position upon base 35 plate 20 by means of a machine screw 22 which is provided with a shoulder 23 and which threadedly engages the plate 20. The pressure exerted between shoulder 23 and plate 20 by screw 22 serves to maintain the relatively stiff contact 40 plate 21 in operable position and plate 21 is prevented from turning by reason of said pressure and by reason of the right angled offset portion 24 which engages the end 25 of the base plate 20. The inner end of contact plate 21 is 45 provided with a right angled forwardly bent integral lug 26 which has the lower surface 27 thereof milled, chased or otherwise roughened, as will be more particularly set forth below. Mounted on the opposite end of plate 20 is an 50 irregularly shaped circuit closing contact plate 28 which is secured in place by a machine screw 29 which threadedly engages the plate 20. Plate 28 is prevented from becoming displaced under operating conditions by reason of the right an- 55

gled offset portion 30 which engages the end 31 of plate 20. The inner end of plate 28 is provided with a forwardly bent integral right angle electrical contact point 32.

5 Pivots mounted on the shoulder 23 of screw 22 is a contact lever 33, the configuration of which is best seen in Figures 1 and 2. The inner or free end 34 of lever 33 is angularly disposed with relation to said lever whereby when the lever 10 is in its upper position, that is, when the end 34 contacts the lug 26, a uniform contact is secured over the entire surface of said lug. End 34 is milled, chased or otherwise roughened on the upper surface thereof so that the fusible material 35 is provided with sufficient surface irregularities 15 to which it may adhere. A cover 36 is shaped as shown in Figure 6 and is provided with large tabs 37 and small tabs 38. As viewed in Figure 6, the tabs 37 and 38 are subsequently bent at 20 right angles to the rear so that the inner surfaces adjacent the outer margins on tabs 37 will lie on the longitudinal edges of the plate 20, as best seen in Figure 5. The cover 36 is secured in place by crimping the same into said edges. The tabs 38 serve to almost completely close the ends 25 of said cover so that dust and moisture are prevented from entering the device 10, thereby prolonging the efficiency thereof.

Operation

30 The device 10 is placed upon the mounting plate 11 by inserting the left end thereof (as viewed on Figure 1) under the screw 15 and then lowering the right end thereof down under the screw 16. It may be noted at this point that owing to the irregular dispersement of the screws 13, 15, 16 and 14 it is impossible to install the device 10 in an upside-down position so that it would then not operate. The outer terminals of 35 the plates 21 and 28 are also suitably cut away as shown at 39 and 40 so that it is a simple matter to connect conducting wires to the screws 13 and 14 without being affected by whether or not the device 10 is in place. When suitable connections have been made connecting the device in series 40 with a source of electrical energy and an electrically operated annunciator, the device acts as a fire alarm. The fusible material 35 is preferably composed of wax or pitch of such a quality that the same will lose its adhesive qualities or will 45 fuse or flow at a predetermined temperature, as for example 110 degrees. When such a temperature is reached the lever 33 falls by the action of gravity away from the lug 26 until the lever contacts the point 32 and assumes the position indicated by the dot-dash lines on Figure 1. In 50 this position the circuit is completed via screw 13, contact strip 18, screw 15, plate 21, screw 22, lever 33, point 32, plate 28, screw 16, contact strip 19 and screw 14. The lever 33 is preferably quite heavy (five ounces has been found satisfactory where the area of lug 26 is about one-quarter inch square but these constants may be varied with changes in the composition of the fusible material 35 or changes in sizes of the various parts). After the device has been acted upon by 55 heat it is a simple procedure for anyone comparatively unskilled to loosen the screws 15 and 16 and replace a similar device at low cost.

60 In the circuit shown at Figure 7 there is illustrated a method by which an ordinary house annunciator system may be used as a fire alarm system. In this figure the electric bell 41 is connected in series with the battery 42 and the push button 43 by means of conductors 44 and 45.

Devices 10 are connected by means of auxiliary conductors 46 and 47 in parallel with the push button 43 and these devices 10 are placed in any locations which are considered desirable or where a fire is more likely to occur. While only two 5 devices 10 are indicated in this diagram, it is obvious that any number may be used where desired and a fire at any point will cause the device to operate, close the circuit and start the bell 41 ringing.

10 I wish it distinctly understood that minor changes in the materials, composition, size, shape and arrangement of the parts herein may be utilized without departing from the scope of the invention or from the spirit of the appended 15 claims.

I claim:

1. A thermoswitch comprising: a base plate; an open circuit contact plate having an offset portion engaging an end of said base plate and 20 having a right angled forwardly bent rigid integral lug; a circuit closing contact plate mounted upon said base plate and insulated from the open circuit contact plate and having an offset portion engaging another end of said base plate and 25 having a right angled forwardly bent integral electrical contact point; means attaching the open circuit contact plate to the base plate; a contact lever pivotally mounted on said means; fusible material disposed between the free end 30 of said lever and said lug and holding the lever and the lug together whereby upon the fusing of said material the lever will drop by the action of gravity and will rest upon the electrical contact point.

35 2. A thermoswitch comprising: a base plate; an open circuit contact plate having an offset portion engaging an end of said base plate and having a right angle forwardly bent integral lug; a circuit closing contact plate mounted upon 40 said base plate and insulated from the open circuit contact plate and having an offset portion engaging the opposite end of said base plate and having a right angled forwardly bent integral electrical contact point; means attaching the open circuit contact plate to the base plate, said means being disposed below the integral lug on the open circuit contact plate; a contact lever pivotally mounted on said means and having the upper surface of the free end thereof angularly disposed with relation to said lever whereby when the lever is in the uppermost position thereof said surface is parallel to the undersurface of the above mentioned lug; fusible material disposed between the free end of said lever and said lug and holding the lever and lug adhesively together, whereby upon the fusing of said material the lever will drop and will rest upon the contact point.

45 3. A thermoswitch comprising: a base plate; an open circuit contact plate having an offset portion engaging the end of said base plate and having a right angle forwardly bent integral lug having a roughened lower surface; a circuit closing contact plate mounted upon said base plate and insulated from the open circuit contact plate and having an offset portion engaging the opposite end of said base plate and having a right angled forwardly bent integral electrical contact point; means attaching the open circuit contact plate to the base plate, said means being disposed below the integral lug on the open circuit contact plate; a contact lever pivotally mounted on said means and having an upper surface of the free end thereof angularly dis- 50 55 60 65 70 75 75

- posed with relation to said lever, whereby when the lever is in the uppermost position thereof said surface is parallel to the undersurface of the above mentioned lug; fusible material disposed between the free end of said lever and said lug and holding the lever and lug adhesively together, whereby upon the fusing of said material the lever will drop and will rest upon the contact point.
4. A thermoswitch comprising: a base plate; an open circuit contact plate having an offset portion engaging the end of said base plate and having a right angle forwardly bent integral lug having a roughened lower surface; a circuit closing contact plate mounted upon said base plate and insulated from the open circuit contact plate and having an offset portion engaging the opposite end of said base plate and having a right angled forwardly bent integral electrical contact point; means attaching the open circuit contact plate to the base plate, said means being disposed below the integral lug on the open circuit contact plate; a contact lever pivotally mounted on said means and having an upper surface of the free end thereof angularly disposed with relation to said lever, whereby when the lever is in the uppermost position thereof said surface is parallel to the undersurface of the above mentioned lug, said angularly disposed upper surface on said lever being roughened; fusible material disposed between the free end of said lever and said lug and holding the lever and lug adhesively together, whereby upon the fusing of said material the lever will drop and will rest upon the contact point.
5. A thermoswitch comprising: an insulating base plate; an open circuit contact plate having an offset portion engaging an end of said base plate and extending outwardly to form an integral mounting lug, said open circuit contact plate having at the inner end thereof a right angle forwardly bent rigid integral tab; a circuit closing contact plate mounted upon said base plate and insulated from the open circuit contact plate and having an offset portion engaging the opposite end of said base plate and extending outwardly to form a second integral mounting lug, said circuit closing contact plate having a right angle forwardly bent integral electrical contact point; means attaching the open circuit contact plate to the base plate; a contact lever pivotally mounted on said means for rotation about a horizontal axis; fusible material disposed between the free end of said lever and said tab and holding the lever and tab together, whereby upon the fusing of said material the lever will drop and will rest upon the contact point; a mounting plate having adjacent one end thereof two projections with a predetermined spacing therebetween and at the opposite end thereof two more projections having a predetermined spacing therebetween which is less than the spacing existing between the first mentioned projections; said mounting lugs having cut out slots adapted to engage the said projections, whereby the base plate may be installed upon the mounting plate in only one position.
6. A thermoswitch comprising: an insulating base plate; an open circuit contact plate having an offset portion engaging an end of said base plate and extending outwardly to form an integral mounting lug, said open circuit contact plate having at the inner end thereof a right angle forwardly bent rigid integral tab; a circuit closing contact plate mounted upon said base plate and insulated from the open circuit contact plate and having an offset portion engaging the opposite end of said base plate and extending outwardly to form a second integral mounting lug, said circuit closing contact plate having a right angle forwardly bent integral electrical contact point; means attaching the open circuit contact plate to the base plate; a contact lever pivotally mounted on said means for rotation about a horizontal axis; fusible material disposed between the free end of said lever and said tab and holding the lever and tab together, whereby upon the fusing of said material the lever will drop and will rest upon the contact point; a mounting plate having adjacent one end thereof two projections with a predetermined spacing therebetween and at the opposite end thereof two more projections having a predetermined spacing therebetween which is less than the spacing existing between the first mentioned projections; said mounting lugs having cut out slots adapted to engage the said projections, whereby the base plate may be installed upon the mounting plate in only one position.
7. A thermal switch comprising: a vertically disposed base plate; a horizontally elongated open circuit contact plate mounted on said base plate in fixed relation thereto and having adjacent one end a forwardly bent rigid integral lug; an elongated contact lever; means pivotally connecting said lever to said contact plate adjacent the end of the latter remote from said lug, said lever having its free end extending beneath said lug; fusible material connecting said lug to, and supporting the free end of said lever; and a horizontally elongated circuit closing contact plate mounted upon said base plate in fixed relation thereto and beneath and insulated from said open circuit contact plate and having a forwardly bent integral electrical contact point adjacent one end and horizontally intermediate said lug and said means and nearer to the latter than to said lug, and adapted upon the fusing of said fusible material and the dropping of the lever under the action of gravity to be engaged by said lever and to hold the latter in a substantially horizontal position.

HERBERT G. HUNT.
